UNITED STATES PATENT OFFICE.

RICHARD PICKHAVER, OF NEW YORK, N. Y., ASSIGNOR TO SONS-CUNNINGHAM REED & RATTAN CO., INC., OF NEW YORK, N. Y., A CORPORATION OF NEW YORK.

DESIGN FOR FRAME OF A CHAIR OR SIMILAR ARTICLE.

Application filed June 17, 1929. Serial No. 31,731. Term of patent 7 years.

To all whom it may concern:

Be it known that I, RICHARD PICKHAVER, a citizen of the United States, residing at New York city, in the county of Queens and State of New York, have invented a new, original, and ornamental Design for the Frame of a Chair or Similar Article, of which the following in a specification, reference being had to the accompanying drawing, forming part thereof.

Fig. 1 is a perspective view, and

Fig. 2 is a side view, of a chair frame embodying my new design, it being understood that the design shown in full lines is repeated at the other end of the chair as indicated by dotted lines.

I claim:

The ornamental design for the frame of a chair or similar article, as shown and described.

In witness whereof, I have hereunto set my hand.

RICHARD PICKHAVER.
